By John F. Hart

15. *Wilson, Dowell, McCann & Rehm*

UNITED STATES PATENT OFFICE

JOHN F. HART, OF ROCKFORD, ILLINOIS

CAN OPENER

Application filed January 22, 1930. Serial No. 422,532.

This invention relates to can openers.

The principal object of my invention is to provide a crank-operated can opener arranged to be mounted on the wall or upon any other suitable support and having provision for quick adjustment to suit cans of different height and of different diameters to enable the opening of cans with much greater ease than with the ordinary hand type and without the ever present danger of injury. I am aware that devices of this general description have been provided in the past but they have been of such complicated and expensive construction as to render the same impractical as a household article. My device, on the other hand, is simple in construction, economical to manufacture, and thoroughly practical for the purpose for which the same has been designed, namely as a household article.

The invention is illustrated in the accompanying drawings wherein—

Figure 1 is a front view of a can opener made in accordance with my invention, certain parts being shown in section for purposes of better illustration; and

Fig. 2 is a plan view of Fig. 1.

The same reference numerals are applied to corresponding parts throughout the views. The device comprises a frame 5 having screw holes at 6 for the fastening of the device onto suitable supporting blocks attached to the wall or onto the side of a cabinet or the like. Cast integral with the frame 5 is a forwardly reaching upper bracket 7 suitably reenforced by a rib 8. A slot 9 extends vertically in the frame 5 and provides a guideway for the inner end of a lower bracket 10 which reaches forwardly from the frame 40 horizontally and in parallel relation to the bracket 7. The bracket 10 is adjustable up and down relative to the bracket 7 by a hand screw 11 bearing at 12 in the bracket 5 and having thrust collars 13 to hold the same against endwise movement relative to the frame. A hand wheel 14 provided with a handle 15 is fixed on the lower end of the screw 11 for turning the same to feed the lower bracket 10 up and down so as to accommodate cans of different heights on the

turn-table 16 beneath the upper bracket 7. The turn-table has a stem 17 bearing in an opening 18 provided in the outer end of the lower bracket 10. The bearing balls 19 received in raceways provided on the under side of the turn-table 16 and on the top of the bracket 10 serve to insure easy turning of the table 16. A washer 20 and screw 21 suffice to keep the turn-table 16 properly assembled on the lower bracket 10. When cans of various diameters are encountered it is of convenience to have the annular grooves 22 in the turn-table 16 to enable centering the cans properly relative to the turn-table.

The upper bracket 7 is slotted, as at 23, 65 where a shaft 24 is mounted therein, the shaft having bearings at the inner and outer ends thereof, as indicated at 25, and being held against endwise movement by a pin 26. The shaft 24 has a key seat 27 therein receiving a pin 28 in a feed roll 29 slidably mounted on the shaft 24. The roll 29 is serrated cross-wise on the periphery thereof for a purpose which will presently appear and has a circular cutting blade 30 either integral therewith or fixed thereto. The blade 30 is slightly larger than the roll 29 so as to pierce the top of the can when the roll 29 is running on the rim thereof. The slot 23 in the bracket 7 is of sufficient size to permit the in and out adjustment of the blade with the roll to suit cans of different diameters. A pair of other slots 31 are provided in the bracket 7 extending in radial divergent relation with respect to the inner end of the slot 23. These slots have elongated idler rolls 32 operating therein received on pins 33 driven into holes provided therefor in the bracket at opposite ends of the slots 31. The rolls 32 project slightly beneath the bracket 7 to about the same extent as the roll 29 so as to ride on the top of the can on the rim portion.

In operation, it will be clear that when a can is placed on the turn-table 16 and centered by reference to the grooves 22 the screw 11 may be turned to feed the can up toward the upper bracket, so that the device is arranged to accommodate practically any can of standard height by suitable adjustment. In the centering thereof the grooves 22 not 100

only facilitate the centering but are arranged to receive the lower rim of the can to grip the same and thus insure against the movement of the can out of position when the same is being opened. These grooves are, of course, provided of any suitable number to take the various standard sized cans. When the can is elevated to about the right height the blade 30 will be adjusted in or out, as required, to bring the same close to the inside of the rim, as clearly appears in Fig. 1, where the can designated by the letter C is indicated in dotted lines. When the blade is positioned in this manner the roll 29 is disposed over the rim and the operator thereupon turns the screw 11 still farther to cause the blade to pierce the top of the can and also press the rim thereof against the roll. The idler rolls 32 bear against the rim of the can at the diametrically opposite side from the feed roll 29 and serve to prevent the can from tipping. The elongation of the idler rolls obviously accommodates the same to a can of any size within the limits of the device. When the crank 35 is turned the roll 29, due to the serration thereof, grips the can at the rim thereof and turns the same with the turn-table 16. The blade 30, meanwhile, cuts through the top of the can alongside the rim in a circular path. It is found that a perfectly smooth cut can be made with the present device and in a fourth or fifth of the time required with an ordinary can opener of the hand type. There is, furthermore, nothing incidental to the use of the device which could possibly give rise to injury to the operator so long as ordinary care is observed.

It is believed the foregoing description conveys a clear understanding of my invention and that it will be agreed that the construction is exceedingly simple considering the utility of the device. It will be apparent that certain changes may be made in various details without departing from the spirit and scope of my invention as expressed in the appended claims.

I claim:

1. A can opener comprising a frame, two brackets projecting horizontally in parallel relation from said frame, a vertical advancing screw acting between said brackets to raise and lower the bracket to accommodate cans of different height therebetween and bring about initial piercing of the can, a turn-table on the lower bracket adapted to support a can, a shaft on the upper bracket extending radially relative to the can received on the lower bracket, said shaft having a crank on the outer end thereof for turning the same, a circular cutting blade turning with but slidable on the shaft to be adjustable in and out to operate on a radius according to the size of the can to be opened, a feed roll turning with the blade and adjusted therewith on the shaft, said roll being of a

smaller diameter than the blade so as to run on the rim of the can to turn the same while the blade pierces the top of the can alongside the rim and cuts the same in the turning of the can, and an idler roll mounted on the upper bracket in a plane parallel with the operating shaft but on the diametrically opposite side of the bracket therefrom, said roll being disposed radially relative to the can received on the lower bracket and operating on the top of the can for the purpose described. 70 75

2. A can opener comprising a frame, two brackets projecting horizontally in parallel relation from said frame, the one being adjustable on the frame up and down relative to the other to accommodate cans of different height therebetween, a shaft on the upper bracket extending radially relative to the can received on the lower bracket, said shaft 80 85 having a crank on the outer end thereof for turning the same, a feed roll turning with but slidable on the shaft to be adjusted in and out according to the size of the can to be opened, arranged to operate on the rim of the can to turn the same in the turning of the shaft, a circular cutting blade also mounted on the upper bracket to turn on a horizontal axis, said blade being likewise freely adjustable in and out to operate on a radius according to the size of the can to be opened, the said blade being of a size such that it pierces the top of the can when the aforesaid feed roll comes into engagement on the rim thereof, and a pair of elongated idler rolls 90 95 mounted on the upper bracket in radially divergent relation on the diametrically opposite side of the bracket from the operating shaft and arranged to turn on horizontal axes, the said rolls projecting beneath the bracket approximately in the plane of the feed roll so as to operate on top of the can. 100 105

In witness of the foregoing I affix my signature.

JOHN F. HART.
